UNITED STATES PATENT OFFICE.

JOHN LE FEVRE, OF TRAER, IOWA.

RAIL-JOINT.

No. 799,740

Specification of Letters Patent.

Patented Sept. 19, 1905.

Application filed March 13, 1905. Serial No. 249,770.

To all whom it may concern:

Be it known that I, JOHN LE FEVRE, a citizen of the United States, residing at Traer, in the county of Tama and State of Iowa, have 5 invented new and useful Improvements in Rail-Joints, of which the following is a specification.

My invention relates to rail-joints, and has for its object to provide a strong and smooth 10 joint between two abutting rail-sections.

In the accompanying drawings, Figure 1 is an elevation of one of the rail-sections, and Fig. 2 a plan view thereof. Fig. 3 is a perspective view of the complete joint.

Referring specifically to the drawings, the 15 two rail-sections are indicated at 5 and 6, respectively. For a distance from their respective ends the rails are cut away diagonally in a vertical plane to form tongues 7 and 8, respectively, which are placed together to form a lap-joint. The meeting 20 faces of the tongues are equally formed, each having a vertical dovetail recess 9 and a correspondingly-shaped tenon 10, the tenon of 25 one rail fitting in the recess of the adjoining rail, as clearly shown in Fig. 1.

In cutting the rails as stated a part of the base-flanges on one side is removed, as at 11, and beyond this the entire sides of the rails 30 are removed to form the tongues 7 and 8. At the outer ends of the tongues the rails are cut, so that a portion of the base-flanges remains, as at 12, forming tongues which fit in the spaces 11, formed by cutting the base- 35 flanges, as already stated. In cutting the base-flanges at 11 a receding shoulder 13 is formed, and a similar shoulder 14 is formed at the inner ends of the tongues 7 and 8, and those portions of the rail which abut against 40 the shoulders are shaped accordingly. As the outer ends of the tongues are quite thin in view of the diagonal cut, the webs are thickened or reinforced, as at 15, in which parts the

bolt-holes 16 are made. The bolt-holes are oblong, and the joint will fit loose enough to 45 permit expansion and contraction.

To form a solid support for the joint and to prevent the rail-sections from tilting upwardly, the joint rests on a number of ties, 50 preferably three, to which the rails are securely spiked, the outer ends of the base-flanges being notched, as at 17, for the spikes.

Having thus described my invention, what is claimed as new, and desired to be secured by Letters Patent, is—

55

1. A rail-joint comprising abutting rails having their ends cut away diagonally in a vertical plane and lap-jointed, the meeting faces of the rails being equally formed, each having a dovetail recess and a tenon, the 60 tenon of one rail fitting in the recess of the adjoining rail.

2. A rail-joint comprising abutting rails having their ends cut away diagonally in a vertical plane to form tongues which are 65 dovetailed together, receding shoulders being formed at the inner ends of the tongues in which the adjoining rail fits.

3. A rail-joint comprising abutting rails having their ends cut away diagonally to 70 form tongues, a portion of the base-flanges remaining at the outer ends of the tongues, and the tongues being dovetailed together, receding shoulders formed at the inner ends of the tongues in which the adjoining rail 75 fits, and a portion of the base-flanges of the rails behind the shoulders being removed in which the remaining base-flanges at the outer ends of the tongues fit.

In testimony whereof I have signed my 80 name to this specification in the presence of two subscribing witnesses.

JOHN LE FEVRE.
